(57) **CLAIM**

The ornamental design for a case for electronic device as shown and described.

DESCRIPTION

FIG. 1 is a back perspective view of a case for an electronic device according to the design.

FIG. 2 is a front perspective view of the case for electronic device shown in FIG. 1.

FIG. 3 is a back view of the case for electronic device shown in FIG. 1.

FIG. 4 is a front view of the case for electronic device shown in FIG. 1.

FIG. 5 is a first side view of the case for electronic device shown in FIG. 1.

FIG. 6 is a second side view of the case for electronic device shown in FIG. 1.

FIG. 7 is a top view of the case for electronic device shown in FIG. 1; and,

FIG. 8 is a bottom view of the case for electronic device shown in FIG. 1.

The broken lines and unshaded surfaces are included to identify parts of the case for electronic device that form no part of the claimed design. The case for electronic device is shown with symbolic breaks in its length and width. The appearance of any portion of the article between the break lines forms no part of the claimed design.

1 Claim, 5 Drawing Sheets
